FLOWER HOLDER

Marion N. Wood, Globe, Ariz.

Application July 22, 1954, Serial No. 31,548

Term of patent 7 years

(Cl. D35—3)

Fig. 1

To all whom it may concern:

Be it known that I, Marion N. Wood, a citizen of the United States, residing at Globe, in the county of Gila and State of Arizona, have invented a new, original, and ornamental Design for a Flower Holder, of which the following is a specification, reference being had to the accompanying drawing, forming part thereof.

I claim:

The ornamental design for a flower holder, as shown.
